FRIDTJOF ANDERSEN, OF TROLLHATTAN, SWEDEN, ASSIGNOR TO TROLLHÄTTANS ELEKTROTHERMISKA AKTIEBOLAG, OF STOCKHOLM, SWEDEN.

METHOD OF ELIQUATING ZINC.

Application filed June 21, 1923. Serial No. 646,897.

To all whom it may concern:

Be it known that I, FRIDTJOF ANDERSEN, a subject of the King of Norway, and residing at Trollhattan, Sweden, have invented 5 certain new and useful Improvements in Methods of Eliquating Zinc, of which the following is a specification.

In zinc, extracted from ores or products containing lead in addition to zinc, the zinc 10 is always mixed with lead in a greater or lesser degree.

The capacity which zinc possesses of dissolving lead is known, to be dependent on the temperature, so that the higher the temperature, the greater, the percentage of lead, which the zinc is able to maintain dissolved. 15 The same condition also concerns any iron present. This property of the zinc has been employed for purifying the same to a certain extent from these two impurities. Said 20 process, which is called eliquation, and which consists in maintaining the spelter or impure zinc at a temperature just above the smelting point, whereby that portion of 25 lead and iron, exceeding the percentage capable of dissolving at the temperature in question, is dissociated and may be separated from the zinc, has hitherto been effected in reverberatory furnaces, heated with coal 30 or oil.

Said furnaces however have certain inconveniences, arising from the manner of heating the furnace. It is of the greatest importance in this process to maintain the 35 temperature as constant as possible, and that a nonoxidizable atmosphere as regards the zinc exists over the bath, or in other words, the atmosphere in the furnace must be neutral or reducing.

The present invention has for its object 40 to overcome these difficulties, and consists in employing radiant electric heat for the carrying out of the process, whereby the temperature can be maintained constant or 45 may be varied to accommodate the process. Moreover the process is performed in an atmosphere, which is maintained neutral or reducing. The employment of radiant heat results in the advantage that contact between 50 the heating elements and the metal under treatment is thereby avoided, and therefore no contamination of the said metal is possible.

Moreover the provision of a non-oxidizing 55 atmosphere about the heating elements

avoids the oxidation both of the elements and the metal under treatment.

A further advantage of the arrangement resides in the fact that a temperature control within very narrow limits is thereby 60 possible.

A constant, or if desired a variable, temperature is obtained in the best manner by employing electrically heated bodies located above the impure zinc under treatment. As 65 material for such bodies there may be used bodies, manufactured of carbonaceous or graphitic materials, mixed with a suitable additional material for establishing the required electric resistance, and the different 70 components may be bound by means of tar, asphalt or any other known adhesive.

Except these above mentioned resistance materials the heating body in certain cases may consist of any known metal alloy with 75 a high electric resistance.

On the accompanying drawing a furnace for carrying out the said eliquation process is shown as an example.

Fig. 1 illustrates the furnace in longitudinal section, whereas Fig. 2 is a horizontal section on the line A—B in Fig. 1. *e* indicates resistance bodies of carbonaceous or graphitic material and *t* resistance members, consisting of metal wires, wound round an 80 insulated pipe *f* or the like. 85

The different resistance bodies shown on the drawing may be employed either each by themselves or in combination with one 90 another.

a indicates the feeding opening for the crude product to be eliquated, *b* the metal bath proper, *c* an opening for the discharge of the purified product, and *d* the tapping 95 device for the eliquated products.

It is clear that in the furnace above described, it will be possible to control the temperature within wide limits, partly by augmenting or diminishing the number of heating bodies, and partly by varying the 100 strength of the current in said resistance bodies.

However it is to be noted that if the resistance bodies are situated in a free space 105 above the zinc bath, as shown on the drawing, they are exposed to oxidation in a high degree, and to deterioration sooner or later, provided the atmosphere surrounding the resistance bodies, is not reducing or at least chemically neutral to the resistance material. 110

In order to establish an atmosphere which is suitable to the electrode material a pipe *g* with a controlling cock *h* is introduced in the furnace, by means of which the furnace 5 can be filled with a suitable gas or with a liquid, which is converted to vapor at the working temperature. If the pipe *g* is made of glass, it will be possible to directly observe the gas pressure in the furnace from 10 outside thereof.

Claim.

Method of eliquating zinc consisting in

smelting impure zinc by means of radiant heat from electric resistance bodies located above the metal under treatment, maintaining a non-oxidizing atmosphere above the molten zinc, and maintaining the temperature required for eliquation. 15

In testimony whereof I have signed my name to this specification.

FRIDTJOF ANDERSEN.
